UNITED STATES PATENT OFFICE.

WILLIAM C. FREE, OF ROCKFORD, ILLINOIS.

FEED MECHANISM FOR SEWING-MACHINES.

1,237,322.

Specification of Letters Patent. Patented Aug. 21, 1917.

Application filed August 7, 1915. Serial No. 44,234.

To all whom it may concern:

Be it known that I, WILLIAM C. FREE, a citizen of the United States, residing at Rockford, Winnebago county, Illinois, have 5 invented certain new and useful Improvements in Feed Mechanism for Sewing-Machines, of which the following is a specification.

My invention relates to the means employed for feeding the fabric or material being sewed a distance corresponding to the length of stitch desired between each reciprocation of the needle. For this purpose it is customary to employ a feed dog consisting of 10 a small plate with a series of pointed projections adjacent to or partially surrounding the needle and connected to suitable means for giving it an advancing movement while projecting above the surface of the head plate and in contact with the material being operated upon, and a reverse movement when withdrawn below the head plate of the machine head. The extent of horizontal movement at each operation corresponds to 15 the length of the stitch desired, and provision is made for adjusting the device to any length of stitch desired. The invention which forms the subject matter of the present application relates to mechanism of 20 this character and for this purpose, which is simple and relatively inexpensive to manufacture, durable, quiet in operation and especially adapted for use in a machine having a constantly operating shaft extending 25 lengthwise of the machine head, as for example for the purpose of operating the shuttle. A machine head of this character is shown in my Patent No. 1,062,389, covering an improvement in shuttle operating 30 mechanism, in which the shuttle is operated by a shaft extending substantially centrally and longitudinally of the head plate of the machine. In my improved feed mechanism such shuttle operating shaft is 35 preferably utilized to operate the cloth feed mechanism.

In the accompanying drawings and in the following specification I have shown and described a preferred form of my invention 40 as applied to a sewing machine head of this type. It is to be understood, however, that the specific disclosure is for the purpose of exemplification only and that the scope of the invention is defined in the following claims in which I have endeavored 45 to distinguish it from the prior art so far 50 as known to me without, however, relinquishing or abandoning any portion or feature thereof.

In the accompanying drawings Figure 1 55 is a bottom plan view of a sewing machine head of the type described in my said patent and showing the preferred form of my invention applied thereto; Figs. 2 and 3 are transverse vertical sections upon the 60 lines 2—2 and 3—3 respectively of Fig. 1; Fig. 4 a horizontal section upon the line 4—4 of Fig. 2 and Fig. 5 a perspective of a detail to be presently described.

The head plate 6 of the machine may be 65 of any known or approved form and is shown as usual of cast metal and formed with bearings 7, 8 for the shuttle operating shaft 9. The specific form of this shaft and its connections are immaterial for the present 70 purpose except as hereinafter specified, but said shaft is shown as driven by pitmen 10, 11 suitably connected to the needle driving shaft of the machine, not shown. The shuttle carrier 12 may be of the construction shown 75 in my said patent and is operated from the shaft 9 in the manner therein described. At the left hand end of the shaft, as shown in Fig. 1, it is formed with offset portions 14, 15 which are circular in cross section and 80 eccentric to the axis of the shaft for the purpose of transmitting to the feed dog the movement above described. The feed dog 16 proper may be of any suitable design and extends as usual through an opening in the 85 head plate into position to feed the material being sewed. Beneath the head plate it is connected as by screw 17 with a carrier plate 18, which is formed as best shown in Fig. 3 with an open-ended horizontal slot which 90 receives the eccentric portion 14 of the drive shaft 9. The carrier plate is formed with a tail piece 19 extending horizontally therefrom and pivoted at 20 to the rocker arm 21 which is pivoted to the casting at 21'. Obviously, if the last-named element were maintained stationary in the position shown in 95 the figures, the revolution of the drive shaft would result in a substantially vertical movement of the feed dog. In order to give the feed dog the necessary feed movement, I provide mechanism for rocking the arm 21 at suitable times in relation to the vertical movement of the feed dog. For this purpose a connecting plate 22 is pivoted at 23 to the 100 rocker arm 21 and at its other end by a screw 24 to a link 25 whose other end is set

cured by a screw 26 to an adjusting arm 27 upon the adjusting shaft 28. Said shaft is frictionally held in its bearings 29, 30 and is angularly adjustable by the finger piece 31 extending through and above the head plate and the graduated arc 32, (see Fig. 5). As seen more particularly in Fig. 2, the rocker arm 21 and link 25 together control the path of movement of the connecting plate 22. The latter is given movement from the cam 15 upon the drive shaft which coöperates for this purpose with a slot 33 formed in said connecting plate. When the drive shaft is revolved it tends to impart a vertical movement to the connecting plate, but such movement is only possible when accompanied by a lateral shift of the connecting plate because of the connections of the latter to the rocker arm 21 and link 25 respectively. The link 25 is always inclined to the horizontal but to a lesser or greater degree according to the position of the finger piece 31. The more closely it approaches the horizontal the less the horizontal movement of the connecting plate required to permit the vertical movement thereof imparted by the eccentric on the drive shaft. By shifting the finger piece and the shaft 28 and arm 27 connected thereto to the normally stationary pivot 26 of the link 27 may be raised or lowered, within a small angle, to adjust the length of stitch to that desired, since the horizontal movement of the dog is substantially that of the connecting plate.

Thus, it will be seen that both the vertical and lateral movement of the dog are derived from the one shaft but from separate cams thereon which may be so designed or angularly displaced about the axis of the shaft

with reference to each other as to properly time the lateral with reference to the vertical movement of the dog and the timing of each with reference to the stroke of the needle may be determined by the angular position of said cams with reference to the eccentric 45 of the shaft by which the shuttle is driven and which in turn is driven from the needle-operating shaft. The vertical movement of the dog being dependent only upon the cam upon the constantly-rotating shaft is invariable, but the lateral movement of the dog may be varied as above described according to the length of stitch desired.

The construction is simple, easy to manufacture, reliable in operation and not easily 55 deranged or injured.

I claim:

In a device of the class described, a revolute shaft, a shuttle carrier, a cam connection between the shuttle carrier and shaft for operating the former, cams on said shaft, a dog carrier, a pivoted arm to the free end of which said dog carrier is pivoted, said carrier being horizontally slotted to embrace one of the cams on said shaft, a dog carried by said carrier, a connecting plate having a substantially horizontal slot engaging the other of said cams, said plate likewise pivoted to said pivoted arm, a shaft adjustable about its axis, a pin eccentrically mounted 60 on said shaft and a link connection between said pin and the end of said connecting plate.

WILLIAM C. FREE.
